[57] CLAIM

The ornamental design for a reclining examination chair, as shown and described.

DESCRIPTION

FIG. 1 is a perspective view of a reclining examination chair showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a front elevational view of the reclining examination chair of FIG. 1, shown in a reclined position;

FIG. 9 is a right side elevational view of FIG. 8;

FIG. 10 is a left side elevational view of FIG. 8;

FIG. 11 is a rear elevational view of FIG. 8;

FIG. 12 is a top plan view of FIG. 8; and,

FIG. 13 is a bottom plan view of FIG. 8.

The broken lines shown in FIGS. 2, 3, 4, 5, 8, 9, 10 and 11 are for environmental purposes only and form no part of the claimed design.
